UNITED STATES PATENT OFFICE.

CHARLES J. CALLAHAN AND GEORGE H. ROBERTS, OF ATTLEBORO, MASSACHUSETTS.

SEPARABLE BUTTON.

1,321,596.

Specification of Letters Patent. Patented Nov. 11, 1919.

Application filed August 9, 1919. Serial No. 316,421.

To all whom it may concern:

Be it known that we, CHARLES J. CALLAHAN and GEORGE H. ROBERTS, citizens of the United States, and residents of Attleboro, 5 in the county of Bristol and State of Massachusetts, have invented certain new and useful Improvements in Separable Buttons, of which the following is a specification.

This invention relates to cuff buttons of 10 the class constructed of two members detachably connected together, and the object of this invention is to provide a cuff button of this class having means for positively locking the two members of the button together and manually operable means for disconnecting these two members thus providing a button whose parts may be readily connected together and which cannot be accidentally pulled apart as is the case with 20 the ordinary separable button.

With these and other objects in view, the invention consists of certain novel features of construction, as will be more fully described, and particularly pointed out in the 25 appended claims.

In the accompanying drawings:

Figure 1— is a side elevation of our improved button.

Fig. 2— is a sectional side elevation 30 through both members of the button, showing the lock-actuating members of the stud.

Fig. 3— is a sectional side elevation showing one member of the button and the supporting members of the stud mounted 35 thereon.

Fig. 4— is a perspective view of the stud member in detail, showing the locking members and also the supporting members of the stud.

Fig. 5— is a top view showing the supporting members of the stud as inclosed 40 within the retaining plate and the operating members as extending through and beyond the periphery of this plate.

Fig. 6— is a view illustrating the blank 45 from which the stud member is formed.

Fig. 7— is a modification illustrating the base end of the socket member in which 50 square retaining shoulders 13 are illustrated.

Our improved button is constructed of 55 two separate members 10, each having a head 11 and a base portion 12, the shank portions of these members being preferably formed hollow. The socket member of this button is constructed at its neck portion 13 to receive and retain the head of the stud 14 of

the opposite button member. This contracted end of the socket member is preferably provided with a flange 15 of convenient size to be passed through the button-hole of 60 a cuff and be retained therein even when disconnected from its associate member of the button.

The stud member of the button is also preferably provided with an out-turned support- 65 ing flange 16 on which flange is mounted the stud 14.

This stud is preferably formed by being first blanked out of sheet stock into the form illustrated in Fig. 6, having two pairs of 70 arms or members 17 and 21 set at right angles to each other. The members 17 are next swaged outwardly forming locking lips 18, see Fig. 4, and the ends 19 of these members are then turned outwardly and are 75 of a length to extend through the binding plate 20 and beyond the periphery of the flange 16. The other two members 21 are bent downwardly to form side walls 22 and their ends 23 are turned outwardly to rest 80 and be supported upon the flange 16 of the stud member of the button.

In order to secure this stud in position on the flange 16 we have provided a binding plate 20 with a central opening 24 to 85 fit over the stud 14 and the edge 25 of this plate is rolled over that of the flange 16, whereby the out-turned ends 23 of the supporting members are gripped and bound securely to this flange holding the stud in 90 the desired position.

At the point where the operating arms 19 pass between this binding plate and the flange the plate is raised a trifle forming a groove through which the operating arms 95 extend and are freely movable.

In constructing this head portion we have formed the members 21 of the stud blank of a width so that when folded they will lie inside the vertical edges of the locking members 17 as best shown in Fig. 4, thereby serving as a convenient stop to limit the inward motion of the locking members when pressed by the thumb and finger of the wearer, to prevent the permanent setting of the spring which might be the case if these members were pressed inwardly too far. 105

In operating this improved button it is only necessary to enter the stud portion 14 110 in the socket member when with a slight pressure on the heads of the opposite but-

ton members the head is easily forced into its socket and the two are firmly and positively locked together and will not be released by any strain which may be brought 5 upon the members. Then when it is desired to separate the members of the button it is only necessary to press inwardly on the operating arms 19, which causes the shoulders 18 to contract sufficiently to dis- 10 engage the inturned edges of the socket permitting the members of the button to be readily separated.

The device is extremely simple and practical in construction and by its use the 15 trouble heretofore experienced with automatically separable buttons is entirely obviated.

The foregoing description is directed solely toward the construction illustrated, 20 but we desire it to be understood that we reserve the privilege of resorting to all the mechanical changes to which the device is susceptible, the invention being defined and limited only by the terms of the appended 25 claims.

We claim:

1. A button comprising two separable members, each having a head and a base portion, the base of one member having a 30 shouldered socket portion, a stud on the other member to releasably engage said socket the same being formed of a metal strip folded upon itself providing opposing resilient legs having engaging lips the 35 ends of said legs being turned outwardly upon the base portion of its member forming manipulating ends whereby said legs may be caused to disengage said socket, and

retaining means for operatively connecting said stud to its base. 40

2. A separable button comprising two separable members each having a head and a base portion, the base of one member having a shouldered socket portion, the base of the other having a flange a stud portion to releasably engage said socket formed of two metal strips each folded upon itself forming two pairs of legs each having its ends turned outwardly and supported by said flange, one pair being provided with laterally 50 extending engaging lips and the turned out ends of this pair extending beyond the periphery of said flange whereby the legs when depressed are caused to release the stud from the socket, and means for rigidly connecting 55 one pair of legs to said flange.

3. A separable button comprising two releasably connected members each having a head and a base portion, the base of one member having a stud-receiving shouldered 60 socket, an elongated stud portion on the other member to releasably engage said socket, said stud being formed of a pair of supporting legs with out-turned ends and a pair of locking legs with out-turned ends 65 longer than those of the supporting legs, said locking legs being depressible through their out-turned ends and provided with engaging lips, and means for rigidly securing said supporting legs to their base, said 70 supporting legs being positioned to limit the releasing stroke of said locking legs.

In testimony whereof we affix our signatures.

CHARLES J. CALLAHAN.
GEORGE H. ROBERTS.
